FRAMING AND FURRING STRUCTURE FOR PARTITIONS, WALLS, AND CEILINGS

Peter Thomson, Wilmington, Del.

Application February 27, 1939, Serial No. 258,825

5 Claims. (Cl. 72—118)

The present invention relates to building construction generally and to improvements in framing and furring structures for partitions, walls and ceilings.

5 An important object of the invention is to provide a nailable supporting member particularly well adapted for use in framing and furring partitions, walls and ceilings in that the member may be nailed at a plurality of points along a rectilinear nail receiving and engaging path formed by a series of closely spaced openings without splitting the member apart along the nail-receiving and engaging path and without loss 10 of purchase of the nails in the nailable member.

15 Another important object of the invention resides in the provision of a nailable metal channel bar which may be employed at the floor or ceiling as a sill or plate and to which may be nailed either end of a supporting member of 20 the character described constituting a wall or partition stud.

Another object of the invention is to provide a longitudinally adjustable telescopic nailable supporting member for use in framing and furring 25 of partitions, walls and ceilings of various dimensions, and wherein the telescopic sections may be secured against movement from a desired position of relative adjustment by the driving of a nail.

30 A further object of the invention resides in the provision of a nailable supporting member having a nail receiving passageway defined by walls adapted to engage or grip a nail driven into the passageway at a plurality of zones.

35 Another object is to provide a nailable supporting member having a nail receiving passageway defined by convergent walls adapted to guide a nail thru the zones of engagement in the passageway.

40 An important feature of the invention is the provision of a nailable supporting member of uniform cross-sectional shape which may be employed not only in the furring of partitions, walls 45 and ceilings, but also in the fabrication of nailable studs for the construction of walls and partitions of various widths.

Another important feature of the invention is to provide a metallic framing structure arranged 50 to facilitate the installation of plumbing pipes and electrical conduits.

Other objects and advantages of the invention will become apparent during the course of the following detailed description, taken in connection with the accompanying drawings, forming a 55

part of this specification, and in which drawings:

Figure 1 is a perspective view of an interior corner of a room showing my improved furring construction applied to the walls and ceiling, certain portions being shown broken away or in section. 5

Figure 2 is a vertical sectional view of a portion of the furring construction including an adjustable wall-carried supporting bracket. 10

Figure 3 is a vertical sectional view of a portion of the furring construction including a ceiling hanger. 15

Figure 4 is a horizontal sectional view of a nailable supporting strip preferably forming a part of the furring construction and showing how a panel of plaster board may be nailed thereto. 20

Figure 5 is a view in side elevation with portions broken away and showing my improved narrow wall and partition framing construction. 25

Figure 6 is a view in vertical cross section of the narrow framing construction.

Figure 7 is a perspective view showing the relationship of sill, stud and plate forming the narrow framing construction. 30

Figure 8 is a horizontal cross sectional view of the stud forming a part of my narrow wall and partition framing construction and showing how a panel of plaster board may be nailed thereto. 35

Figure 9 is a perspective view of an end portion of channel beam employed for framing over or under a wall opening.

Figure 10 is a view in side elevation with portions broken away and showing my improved wide wall and partition framing construction. 40

Figure 11 is a view in vertical cross section of the wide wall and partition framing construction.

Figure 12 is a fragmentary perspective view showing a portion of the stud forming a part of the wide framing construction. 45

Figure 13 is a fragmentary horizontal sectional view of the wide stud.

Figures 14 and 15 are perspective views of a plate and sill preferably employed in the wide framing construction. 50

In the drawings, which show preferred and modified forms of the invention, and wherein similar reference characters denote corresponding parts thruout the several views, the letter A generally designates the improved furring construction for a wall or ceiling, including nailable supporting members B and adjustable brackets C; the letter D generally designates a narrow type framing construction for a wall or partition, 55

including nailable narrow type studs E and nailable narrow type channel beams F for use as sills and plates; and the letter G generally designates a wide type framing construction for a wall or partition, including wide type studs H, each utilizing a pair of nailable supporting members B, and nailable wide type channel beams J for use as sills and plates.

Referring to the furring construction A, the same is shown in Figure 1 as applied to a room including a concrete floor 25, a concrete ceiling 26 and brick walls 27. Secured in depending relation from the ceiling 26, as by molding therewith at the time the ceiling is cast, is a plurality of spaced hangers 28 carrying channel bars 29, preferably in parallel relation to one of the side walls of the room. Secured subjacent the channel bars 29, as by wiring 30, and preferably in perpendicular relation thereto, is a plurality of spaced nailable supporting members B.

Secured in projecting relation from the brick walls 27, as by setting in mortar 31 between vertical joints, preferably at the time the wall is constructed, is a plurality of spaced adjustable brackets C to which are secured, as by wiring 32, inverted channel bars 33, paralleling the floor. Secured to the channel bars 33, and preferably in perpendicular relation thereto, as by wiring 34, is a plurality of spaced nailable supporting members B. At the room corners, the channel bars 33 of adjacent side walls may cross one another.

Referring now to the nailable supporting members B in detail, each may comprise a channel beam 35 including a reentrant dihedral angular web 36, and side flanges 37 including convergent sections 38 extending from opposite sides of the web and coplanar divergent sections 39 continuing from the convergent sections 38. Provided along the vertex of each dihedral web 36 is a series of nail-receiving circular openings 40 preferably of a diameter slightly less than that of a given nail 41. These circular nail-receiving openings 40 are preferably closely spaced. As an example, the distance between centers of adjacent openings 40 preferably is no greater than twice the diameter of the openings. The side flanges 37 at the junctures of their convergent and divergent sections 38, 39 are preferably spaced a distance less than the diameter of the given nail 41. Extending over the divergent sections 39 is a puncturable metal binding strip 42 having its marginal edge portions 43 folded around the divergent sections in a manner to provide cavities 44, adjacent the folded portions as shown in Figure 13, permitting slight spreading of the divergent sections, upon driving of a nail into the member B. In Figure 4, the nail 41 has spread the flange sections 39 apart so that the cavity space is occupied. The convergent surfaces of the dihedral web and side flanges serve to guide a nail 41 thru one of the nail-receiving openings 40 and between the closely spaced junctures of the side flange sections 38, 39, and then into puncturing engagement with the binding strip 42.

The adjustable brackets C may each include a socket member 45 and a bolt 46.

The bolt 46 may be formed with a lug 58 at its outer end for carrying the inverted channel bar 33.

In the example shown, plaster board panels 61 are secured, as by nails 41, to the nailable supporting members B of the furring construction A to provide wall and ceiling surfaces, but it will be understood that the surfaces may be of any suit-

able material, such as plaster, and that expanded metal or wood lath, as well as the usual plaster ground strips may be attached to the supporting members C by nailing.

Referring now more particularly to Figures 5-8 of the drawings, the narrow width framing D for walls and partitions is shown as applied between a floor 75 and ceiling 76. A plurality of nailable studs E may be employed, each comprising a channel beam 77 including a reentrant dihedral web 78, and side flanges 79 comprising convergent sections 80 extending from opposite sides of the web 78 and divergent sections 81 continuing from the convergent sections. The web 78 is provided with a series of nail-receiving openings 40 like those in the web 36 of the member B, and the junctures between the sections 80-81 are spaced in a manner similar to the spacing of the junctures of the side flange sections 38-39. Each nailable stud further comprises a nailable channel beam 82 including a reentrant dihedral web 83 and convergent side flanges 84 engaging the divergent sections 81 of the beam 77. The web 83 is also provided with a series of nail-receiving openings 40.

Telescopically related to the channel beams 77-82 is a sleeve member 85 having reentrant dihedral sides 85' similar to and slidable outwardly of the reentrant dihedral webs 78-83, whereby the sleeve member may be fixed against telescopic sliding movement from an adjusted position by merely driving a nail thru aligning openings 40.

Channel beams F may be employed to form the sill 86, plate 87 and horizontal support 88 for use above or below a wall opening. In Figure 5, the horizontal support 88 constitutes a header for a door opening but it will be readily understood that the support 88 may be employed above or below a window opening. Each beam F comprises a central web 89 provided with a series of apertures 90 for the accommodation of electrical conductors and the like, and side flanges 91 provided with a series of nail-receiving openings 92 for the securement of the narrow stud E in any of a plurality of positions along the channel beam F, by nailing.

It will be seen that this framing construction D is adjustable to various ceiling heights and may be readily provided on opposite sides with suitable surfaces such as the plaster board panel 93, by nailing. In order to facilitate framing of openings, the web 89 of the channel beam F may be severed along its junctures with side flanges 91, as shown in Figure 9, and turned to form an abutment flange 94.

As for the framing construction G for a wide wall or partition, attention is invited to Figures 10-15 of the drawings. The wide type studs H each preferably comprise a pair of nailable supporting members B of the character described. Securing these nailable supporting members B in spaced relation is a plurality of cross-ties 100 each comprising a pair of strips 101 united intermediate their ends as by welding 102 and having their end portions 103 folded into gripping engagement with opposite sides of the flange binding strips 42 of the spaced members B.

Telescopically related to the supporting members B are spaced apart relatively short sections 70 of channel beam 35 of the character described, and connected by cross-ties 100, as described, having their end portions 103 foldably engaging the divergent side flange sections of the beam 35.

Relatively wide channel beams J may be em-

ployed to form a sill 104, plate 105 and horizontal support 106 for use above or below a wall opening. In Figure 10, the horizontal support 106 constitutes a header above a door opening but it will be readily understood that the support may be employed as a stretcher below a window opening. Each beam J comprises a central web 107 provided with a series of apertures 108 for the accommodation of the relatively large drain and vent pipes often encountered in the building industry, and side flanges 109 each provided with a series of nail-receiving openings 110 for the securement of the wide type stud H in any of a plurality of positions along the channel beam J, by nailing.

It will therefore be seen that this wide type of framing construction is adjustable to various ceiling heights and may be readily provided on either or both sides with suitable panel surfaces.

The stud H may be economically produced in a quantity of widths as the cross-ties 100 are the only portions which require variation.

It will therefore be observed that the nailable supporting member B, stud E and stud H herein described, each provide channel beams having a passageway for the reception, and engagement of a driven nail, and defined by walls adapted to guide the drive nail toward the zones of engagement.

Various changes may be made in the forms of invention herein shown and described without departing from the spirit of the invention or the scope of the following claims.

I claim:

1. A nailable supporting member comprising a channel beam including a reentrant dihedral web, and side flanges including convergent sections extending from opposite sides of the web and divergent sections extending from said convergent sections, said dihedral web being provided along its vertex with a series of nail-receiving openings and said side flanges at the junctures of said convergent and divergent sections being spaced apart a distance no greater than the diameter of said nail-receiving openings and means spanning said divergent sections for maintaining said side flanges in spaced relation.

2. A nailable supporting member comprising a channel beam including a reentrant dihedral web, side flanges including convergent sections extending from opposite sides of the web and divergent sections extending from said convergent sections, said dihedral web being provided along its vertex with a series of nail-receiving openings and said side flanges at the junctures of said convergent and divergent sections being spaced apart a distance no greater than the diameter of said nail-receiving openings, and a puncturable sheet secured in spanning relation to said divergent sections for maintaining said side flanges in spaced relation.

3. A nailable supporting member comprising a channel beam including a reentrant dihedral web, side flanges including convergent sections extending from opposite sides of the web and divergent sections extending from said convergent sections, and a second channel beam including a reentrant dihedral web and side flanges including convergent sections extending from opposite sides of the web of said second channel beam, the convergent sections of said second channel beam being disposed in exterior surface engagement with the divergent sections of said first channel beam, said dihedral webs being each provided along their vertices with series of nail-receiving openings and the side flanges of said first channel beam at the junctures of their convergent and divergent sections being spaced apart a distance no greater than the diameter of said nail-receiving openings.

4. A nailable supporting member comprising a pair of channel beams each including a reentrant dihedral web, and side flanges including convergent sections extending from opposite sides of the web and divergent sections extending from said convergent sections, said dihedral webs each being provided along their vertices with series of nail-receiving openings and said side flanges at the junctures of their convergent and divergent sections being spaced apart a distance no greater than the diameter of said nail-receiving openings, said channel beams being disposed in parallel relation with said divergent sections secured to the divergent sections in spanning relation to said channel beams for maintaining said beams in fixedly spaced relation and for maintaining said junctures against spreading upon passage of a nail therebetween.

5. A nailable supporting member comprising a pair of channel beams each including a reentrant dihedral web, and side flanges including convergent sections extending from opposite sides of the web and divergent sections extending from said convergent sections, said dihedral webs each being provided along their vertices with series of nail-receiving openings and said side flanges at the junctures of their convergent and divergent sections being spaced apart a distance no greater than the diameter of said nail-receiving openings, said channel beams being disposed in parallel relation with said divergent sections confronting one another, and means disposed in spanning relation to said channel beams for maintaining said beams in fixedly spaced relation, said means comprising a plurality of spaced crossbars each including a pair of straps having their end portions secured to the divergent sections and having their intermediate portions secured together remote from said divergent sections whereby a nail may be driven between said strap end portions.

PETER THOMSON.
